(57) **CLAIM**

The ornamental design for a combined light shade and canopy, as shown and described.

DESCRIPTION

FIG. 1 is a perspective front side bottom view of a combined light shade and canopy.

FIG. 2 is a perspective front side top view thereof.

FIG. 3 is a front side view thereof.

FIG. 4 is a left side view thereof.

FIG. 5 is a rear side view thereof.

FIG. 6 is a right side view thereof.

FIG. 7 is a bottom view thereof; and,

FIG. 8 is a top view thereof.

The broken line showing of the ceiling canopy, vertical support rod, internal light fixture, internal cone and multi part tip in FIGS. 1-8 are for illustrative purposes only and forms no part of the claimed design.
